UNITED STATES PATENT OFFICE.

A. COLTON, OF LE ROY, NEW YORK.

VALVE-PROPELLER.

Specification of Letters Patent No. 20,332, dated May 25, 1858.

To all whom it may concern:

Be it known that I, AARON COLTON, of the town of Le Roy, in the county of Genesee and State of New York, have invented certain new and useful Improvements in Propellers; and I do hereby declare that the following is a full, clear, and exact description of the same, reference being had to the annexed drawings, making a part of this specification, in which—

Figure 1, represents a vertical longitudinal section of my improvements, *x*, *x*, Fig. 2, indicating the plane of section. Fig. 2, is a plan or top view of the same and, Fig. 3, is a transverse, vertical section of one of the sliding frames, *y*, *y*, Fig. 2, indicating the plane of section.

Similar letters of reference indicate corresponding parts in the several figures.

This invention relates to paddles placed in horizontal sliding frames and it consists in attaching the same by means of pivots, between their centers and their upper edges to these frames, the upper edges being guided by loops, which are attached to horizontal plates which are placed on the top of the sliding frames in such a manner that they assume a separate sliding motion, independent from the motion of the frames, whereby the paddles are inclined either one way or the other, and it further consists, in a peculiar arrangement of stops, which are so constructed, that by placing the same either on one side of the paddles or on the other the latter are made to propel the vessel forward or backward, and that by releasing the stops altogether the paddles move both ways with the sliding frames without any effect in propelling the vessel either in one direction or the other.

To enable others skilled in the art to fully understand and construct my improvements I will proceed to describe the same.

A, is a frame work which forms the support for two or more pairs of horizontal ways *B*, and which is supposed to be attached to the stern of a vessel. The ways *B*, form the guides for the sliding frames *C*, *C'*, in which the paddles *D*, are arranged, each frame carrying 2 or more paddles. Plates *E*, are placed loosely on the top of the frames *C*, *C'*, being held in their position by the rods *a*, which form a staple on each side of the frame for the plates to pass through; and loops *b*, are rigidly attached

to the under sides of these plates, at suitable distances. The paddles are attached to the sides of the frame *C*, by means of pivots *c*, which are fastened to the paddles about midway between their centers and their upper edges, and openings *d*, are cut in the middle of the paddles from the upper edges down to some distance to make room for the loops *b*. Rods *e*, which are rigidly attached to the upper edges of the paddles, pass loosely through the loops *b*.

Ears *f*, are provided on the upper sides of the plates *E*, to which connection rods *F*, are attached, which extend to a crank shaft *G*. Two cranks *G'*, *G''*, are provided on this shaft in opposite directions so that the sliding frames assume a reciprocal motion. Horizontal rods *g*, are attached to each side of the frames *C*, having their bearings in projections *h*, which are rigidly fastened to the sides of the frames, and the hooks *i*, extend from said rods downward, the hooks being placed at such distances on the rods *g*, that they correspond to the position of the paddles, and these hooks extend through the sides of the frames *C*, as clearly shown in Fig. 3, and form the stops of the paddles *D*. Small springs *j*, keep these stops in their position. Short arms *k*, extend from the rods *g*, in a horizontal direction and rods *l*, are provided which extend from one end of the ways *B*, to the other, having their bearings in the ears *l'*. The ends of these rods, which are nearest to the vessel, are bent upward, forming the loops *m*, and those parts of said rods which run alongside and under the ways *B*, are bent so as to form a sort of cranks, extending from one end of the ways *B*, to the other. The arms *k*, extending from the rods *g*, rest on the rods *l*, and a string *n*, is attached to the loops *i*, which may be extended to the inside of the vessel.

The operation is as follows:—The crank shaft *G*, is turned so that the sliding frames *C*, *C'*, are moved in the direction of the arrows. The paddles *D*, attached to the frame *C*, which moves in the direction of arrow 1, are arrested in a vertical position by the stops *i*, and they will therefore, by coming in contact with the water (as shown in Fig. 1) propel the vessel in the direction of arrow 3. At the same time the sliding frame *C'*, moves in the direction of arrow 2, and the paddles attached to this frame being re-

leased by the stops *i*, are left free to be inclined as shown in Figs. 1 and 2. The paddles are inclined by the action of the plates *E*, for whenever a strain is exerted on these 5 plates which tends to move the same in a horizontal direction, the loops *b*, will bear against the rods *e*, on the upper edges of the paddles *D*, and have a tendency to turn the same on the pivots *c*. The paddles *D*, therefore will be inclined either one way or the other according to the action of the cranks *G'*, *G²*, on the plates *E*, unless prevented from being inclined by the stops *i*. It is obvious for this reason that by releasing the 15 stops *i*, the paddles are inclined in going backward as well as in going forward and they will not have any effect in propelling the vessel. If however the stops *i*, are put on the outside of the paddles (away from 20 the vessel) the latter will be arrested in a vertical position while moving in the direction of arrow 4, and the motion of the ves-

sel will be retarded or the vessel will be propelled backward.

The stops *i*, are operated by the rods *l*; 25 by pulling the string *n*, the loops *m*, are turned down, whereby the crank parts of the rods *l*, are turned up to a position shown in red outlines (Fig. 3) and the stops *i*, are pulled back. As soon as the string *n*, 30 is released the stops *i*, drop into their places by the action of the springs *j*.

Having thus described my invention what I claim as new and desire to secure by Letters Patent, is,

35 The connection of the paddles with the sliding frames *C*, *C'*, and the flat plates *E*, in combination with the stops *i*, constructed and operated substantially as described.

AARON COLTON.
